UNITED STATES PATENT OFFICE.

WILLIAM WRIGHT, OF CHICAGO, ILLINOIS, ASSIGNOR TO E. PAYSON SMITH, OF SPRINGFIELD, ILLINOIS.

BRAKE-GEAR MOUNTING.

Application filed April 10, 1926. Serial No. 101,156.

My invention relates to the gear housing and method of mounting the same to the transverse member or end sill of a car underframe. The invention has for its object the provision of a stable single piece gear housing; the top whereof is formed to permit ready attachment to the end sill to be made, while at the same time providing reinforcement or compression elements intermediate of the top of the housing and the transverse member or end sill of the car underframe whereby the pulling strain exerted on the gear mounting or housing during application of the brakes will be transferred in the opposite direction to the cross-member or end sill of the car underframe.

The invention and its objects will be readily comprehended from the following detailed description of the accompanying drawings, wherein:

Figure 1 is a front elevation of my improved gear housing and method of mounting; the brake-staff and car frame member being broken away.

Figure 2 is a top plan view of the same.

Figure 3 is a vertical sectional view taken substantially on the line 3—3 of Figure 2.

Figure 4 is a front elevation showing a modification of the invention.

Figure 5 is a top plan view of the construction shown in Figure 4.

Figure 6 is a sectional elevation thereof, the view being taken substantially on the line 6—6 of Figure 5.

Figure 7 is a front elevation showing another modified form of my invention.

Figure 8 is a top plan view thereof and

Figure 9 is a sectional elevation taken substantially on the line 9—9 of Figure 8.

My invention contemplates a single piece housing comprising a top 10 and two side walls 11, 11 formed integral with the top. The main portion of the top 10 is shown substantially rectangular in Figure 2, with the forward side provided with a forwardly projecting portion 12, shown of less length than the main portion; the portion 12 terminates in the arcuate top extension 13 shown disposed in a lower plane than the portion 12 and the main top 10.

The portion 12 and the extension 13, as well as a portion of the main top 10, are intended to project forward of the end sill 14 of the car underframe. It will be under-

stood of course, that the two side walls 11, 11 of the housing are formed to correspond with the inset portion 12 (relative to the normal side edges of the top as viewed in Figure 2) and with the off-set arcuate extension 13. The projection 12 and extension 13 are for the purpose of covering a part of the drive gear portion of the gearing; the side walls 11, 11 at this forward part of the housing therefore are shown of less vertical depth than the sides of the main part of the housing, as more clearly shown in Figure 3; the main portion of the sides being extended downwardly a distance sufficient to encase the operating mechanism which is more or less schematically shown, as the gearing in itself forms no part of this application. The side walls 11, for the sake of lightness, may be provided with openings as shown at 15. What may be termed the rear side of the housing is open.

The off-set narrower portion at the front of the housing is provided with a chair or narrow plate 17 having downwardly disposed flanges and ends; the latter being riveted at 18 to the side walls of the forward off-set portion of the housing and forms a supporting bridge for the drive member 16 of the gearing and a bearing for the lower end of the brake-staff 19 which extends through the top 10 of the housing; the staff thus being provided with two spaced apart bearing points which firmly hold the staff in proper position.

The top portion 10 of the housing is preferably provided with an enlargement or boss about the opening of the brake-staff 19; the opening being sufficient to also receive the extended hub of drive gear 16 as shown in Figure 3; while the chair or narrow plate 17 on its upper surface is provided with a socketed boss adapted to receive the downwardly disposed hub portion of the drive gear 16 to maintain the latter in place; the socketed boss being disposed about the opening through the chair or narrow plate 17 through which the lower reduced end of the brake-staff 19 extends.

The rear part of the housing is provided with a transversely disposed bottom portion 20 formed integral with the sides 11, 11.

The bottom portion 20 provides support for the driven gear 21 and the chain winding drum indicated at 22. The bottom portion

20 being apertured to receive the reduced portion of the elongated hub 21^a of the driven gear which hub portion passes through the winding drum or spool 22 and has its 5 immediate end reduced for passage through the opening in the bottom 20. The spool 22 is caused to rotate with the driven gear 21 by squaring the portion of the extended hub of the driven gear at the point where it 10 receives the spool 22. The driven gear 21 with the spool 22 are rotatably held in the housing by means of the pin 23 which is disposed through an opening in the top of the housing, through the hub of the driven gear 21 and therefore through the opening in the bottom 20; accidental removal of the pin being prevented by any suitable means, as for example a cotter-pin. In this type of 15 housing and construction, vertical play or 20 movement of the driven element is prevented by means of a washer 23^a arranged intermediate of the top of the housing and the driven gear 21 as shown in Figure 3.

The housing in cross-section comprises a 25 three sided figure consisting of integral top and two side walls, which are reenforced by the removable chair or plate 17 and transverse wall 20 which is formed integral with the side walls.

30 The top 10 of the housing is provided with a plurality of vertically disposed webs 24 which, at the forward portion, preferably terminate at the top in a horizontally disposed web or plate 25. The front longitudinal edge of plate 25 is formed with an 35 upstanding lip 26, adapted to engage the front of the lower flange of the end sill 14.

The webs 24 may be continuous from front 40 to rear of the top of the housing, with the rear portion 27 of the webs 24 extending to a greater height than the forward portion. The portion 27 of the webs 24 are connected together by an integral web 28 which is 45 adapted to extend flush with the rear side of the end sill 14 to which it is secured by rivets as at 29.

The horizontally disposed connecting web 25 is shown riveted at 30 to the lower flange of the end sill and constitutes the main 50 attaching portion for pendently securing the housing to the bottom of the end sill; while the elongated rear portions 27 of the webs 24 constitute compression means adapted to transmit the rearward pulling strain 55 encountered by the housing to the end sill of the car underframe and thus taking care of the shearing strains on the rivets 30 which secure the housing to the lower flange of the end sill. The shearing strains are also 60 taken care of by the marginal lip 26 disposed full length of the forward edge of the top portion or web 25.

In Figures 4 to 6, I show a modification in 65 so far as the mounting of the gear housing is concerned; the housing, like in Figures 1

to 3, comprising a top 10 and two side walls 11, all substantially of the same general configuration as in Figures 1 to 3, so as to provide a gear housing open at bottom, front and rear sides. The housing is likewise 70 provided with the chair or plate 17 for supporting the driven elements of the gearing; while the driven elements, like in Figures 1 to 3, are supported by the transverse wall 20 formed integral with the lower ends of the 75 two side walls 11; the construction and mounting of the gearing being the same as in Figures 1 to 3.

In the construction in Figures 4 to 6, the 80 top is provided at a point intermediate of the front and rear edges with the integral and vertically disposed brackets 31 arranged in spaced relation and adjacent opposite sides of the housing as shown in Figure 4.

The brackets preferably consist of the web 85 portions 32 disposed in a direction transversely of the end sill 14 and the laterally and downwardly flaring webs 33, see Figure 4; the webs 32 and 33 terminating at top in a horizontally disposed plate 34 adapted to 90 extend flush with the bottom of the end sill 14; the front and rear edges of the plate 34 being bent upwardly or flanged as shown at 35, 35 which engage with and lap the lower part of the end sill 14 at the front and 95 rear sides of the sill, see Figure 6.

The top 10 of the housing in this construction differs from that shown in Figures 1 to 3 in that it is not provided with the upwardly disposed rear extensions 27 and 100 webs 28; while the top 10 of the housing, for the sake of lightness, is shown provided with a pair of rearwardly disposed extensions 36, 36. These extensions 36, 36 provide attaching points for the lower ends of brace bars 105 37, 37, which extend forwardly at an upward inclination for attachment to the rear or inner side of the end sill 14. These bars have their ends bent at a suitable angle so that the lower ends of the bars 37, 37 may 110 be riveted or otherwise secured to the top extensions 36 of the housing as shown at 38; while the other ends of the bars are disposed parallel with the rear side of the end sill and shown riveted thereto at 39. With this construction, the housing will be firmly braced 115 against the pull of the chain when the latter is wound on the drum or spool 22 during brake-applying operations.

In Figures 7 to 9, inclusive, I show still 120 another modified form of my invention, which, like in the previously described constructions, comprises a single piece housing consisting of the top 40 and two side walls 41; the top having more or less of the same 125 configuration at the forward end of the housing as in the previously described constructions so as to overlap or enclose the drive element of the gearing. In this construction, like in the other constructions, the 130

brake-staff 19 is provided with a plurality of bearing points in the housing; first in the top of the housing, where the brake-staff enters the upwardly disposed hub portion of the drive gear 16; while the lower portion of the staff passes through an aperture in the socketed boss formation of the chair or plate 17 which may be identical in construction with that shown in Figures 3 and 6 and 10 which is suitably riveted to the side walls 11 of the housing at the forward end thereof.

The chair or plate 17 is formed to receive the downwardly disposed hub portion of the drive gear 16 like in the other constructions.

15 In the construction illustrated, in Figures 7 to 9, the gear housing is intended to be directly secured to the underside of the end sill 14 and therefore the top 40 is in immediate contact with the bottom flange of the 20 end sill; the top 40 being provided with a transversely extending rib 42 adapted to abut against the forward edge of the lower flange of the end sill while the rear end of the top 40 is provided with an upstanding 25 rib 43 adapted to extend flush with the rear side of the end sill 14; the rib 43 being reinforced by a suitable number of webs 44; the upstanding rib 43 being intended to be riveted to the end sill as shown at 45. The top 30 40 is riveted at 46 directly to the lower flange of the end sill; such riveting being possible because of the fact that the bottom and forward and rearward ends of the housing are open; the riveting of the housing in place 35 may be accomplished before inserting the gearing into the housing; as this may be readily accomplished by reason of the fact that the bearings and supports for the gearing and brake-staff are in the nature of removable chairs or plates. The side walls 41 of the housing are also preferably shown provided with openings as at 47 which will also enable easy access for the purpose of riveting the housing in place.

45 In this construction, the driven gear 21 and spool or drum 22 are supported in place by a chair or plate 48 which is riveted or secured in place after the driven elements have been inserted into the housing and in proper relation with the chair or plate 48. As the plate or chair 48 is arranged at the lower edge of the side walls and therefore in a lower plane than the plate or chair 17, the ends of the plate or chair 48 are disposed 50 upwardly as shown at 49 in Figure 7 so as to be disposed parallel with the side walls 41, 41 to which the ends are riveted at 50 or otherwise suitably secured thereto.

With the bearing for the driven elements 60 insertible into place as described, the method of journaling the driven element in this construction is slightly different from that previously described in that the journal pin 23 is eliminated, as the driven gear 21 is shown 65 provided with an upwardly disposed trun-

nion 51, see Figure 9, disposed through an opening in the top 40 in the housing; the opposite side of the gear 21 being provided with an extended hub portion similar to that previously disclosed to receive the spool or 70 drum 22 arranged on the squared portion of the hub so as to rotate therewith; the spool resting on the chair or plate 48 which is apertured to receive the lower reduced rounded portion 52 of the hub or trunnion 75 of the gear 21.

The constructions shown and described 80 permit arrangement of the gear housing in different horizontal planes and therefore in keeping with the varying constructions employed in railroad practice in order that the chain-receiving drum or spool of the driven elements may be in proper position or alignment with the chain and brake-applying mechanism. The constructions consist of a 85 single piece housing composed of a top and two side walls in conjunction with lower bearing providing portions for the drive and driven elements; said bearing providing portions being in the nature of transversely disposed chairs or plates preferably removably secured in place. With these constructions 90 it will be seen that the brake-staff is provided with a number of bearing points above and beneath the drive element of the gearing. 95

The invention has been disclosed in what is believed to be the simplest embodiment thereof and has been described in terms employed merely as terms of description and not as terms of limitation as modifications 100 are possible without, however, departing from the spirit of my invention.

What I claim is:

1. Brake gear mountings, comprising a single piece housing having integral top and two side walls, the upper surface of the top being provided with a transversely disposed end-sill engaging portion, an elongated narrow plate having flanged ends secured to the side walls adjacent to the forward end of the housing, said plate being formed to provide a bearing and support for the brake-staff and drive gear, and a second elongated narrow plate attached at its ends to the side walls adjacent to the rear end of the housing and formed to provide support and bearing for the driven element.

2. In combination with a car end-sill of channel cross-section, a single piece housing composed of top and two side walls and adapted to be secured to the bottom of the end-sill, the top being provided with an integral upstanding portion adapted to abut against the forward edge of the lower flange of the end-sill, brace-bars secured at their lower ends to the inner end of the housing-top while their upper ends are secured to the rear side of the end-sill, and a pair of gear element supporting plates attached at their ends to the side walls of the housing adja-

cent to the forward and rear ends of the housing.

3. In combination with a car end-sill, a gear housing composed of integral top and side walls, the top being provided with positioning means adapted to abut the lower longitudinal edges of the end-sill, bracing means intermediate of the inner end of the housing top and the rear side of the end-sill, and a pair of plates, the ends whereof are attached to the side walls of the housing and constituting, respectively, supporting means for the drive and driven elements of the gearing.

15 4. In combination with a car end-sill, a single piece housing adapted to be secured to the bottom of the end-sill and composed of integral top and side walls, the top being provided with upstanding portions adapted to engage with the inner and outer sides of the lower part of the end-sill, a chair or plate removably secured at its ends to the side walls of the housing and socketed to provide bearing for the lower end of the 20 brake-staff and drive element, and a plate attached at its ends to the side walls adjacent to the rear side of the housing for supporting the driven elements in place.

5. Brake gear mountings, comprising a 30 single piece housing having integral top and side walls, the housing being open at front and rear, with the top provided with upstanding projections adapted, respectively, to abut against the lower flange of the car 35 end-sill and to engage with rear side of the end-sill, and a pair of narrow plates attached at their ends to the side walls of the housing, one plate constitutes a support for the brake-staff and drive element of the gearing while 40 the other plate constitutes a support for the driven elements.

6. Brake gear mountings, comprising a single piece housing having integral top and two side walls, the top being adapted to be 45 secured to the bottom of a car end-sill and having a transversely disposed upstanding portion adapted to abut against the lower flange of the end-sill, bracing means intermediate of the rear end of the housing and rear side of the end-sill, and a pair of staff 50 and gearing supporting plates attached at their ends to the side walls of the housing, both of said plates being apertured to receive the extended hubs of the drive and 55 driven elements, respectively.

7. Brake gear mountings, comprising a housing composed of an integral top and two side walls, upstanding webs integral with the top and terminating at the top in a 60 transversely disposed portion adapted to engage with the bottom of a car end-sill, said portion being formed to engage the front and rear longitudinal edge of the end-sill, bracing means secured to the rear end 65 of the housing and adapted to be secured to

the rear side of the end-sill above the bottom thereof, and a pair of horizontally disposed gear supporting elements extending from side wall to side wall adjacent, respectively, to the front and rear ends of the housing and 70 arranged in different horizontal planes.

8. In combination with a gear housing composed of an integral top and two side walls, and a pair of supporting plates attached at their ends to the side walls, of 75 gearing comprising a drive gear apertured for passage of the brake-staff therethrough and having an extended hub rotatably mounted on one of said plates, a driven gear provided on one side with an extended hub rotatably mounted on the other plate, and a spool mounted on said extended hub so as to rotate with the driven gear.

9. Brake gear mountings, comprising a 80 housing composed of an integral top and two side walls, the top being adapted to extend flush with the bottom of a car end-sill and be secured directly thereto and having a transversely extending positioning rib for abutment against the lower longitudinal 90 edge of the end sill, a pair of gear supporting plates disposed transversely of the forward and rearward ends of the housing, the ends of the plates being flanged and attached to the side walls of the housing. 95

10. Brake gear mountings, comprising a 100 housing composed of an integral top and two side walls, a pair of gear supporting plates within the housing adjacent to the front and rear ends of the housing, the ends 105 of the plates being attached to the side walls, and brace means extending from the rear end of the top of the housing to the rear side of the car end-sill to which said means are adapted to be secured.

11. A brake gear mounting, comprising a 110 housing composed of an integral top and two side walls and a pair of removable gear element supporting plates arranged, respectively, between the side walls adjacent to the front and rear ends of the housing, the forward plate being apertured to receive the lower end of a brake-staff and having a circumferential rib about the aperture to provide a socket for the lower end of the 115 drive gear hub, while the rear plate is apertured to receive the lower end of the driven gear hub, and means for securing the driven gear in place.

12. In a brake gear mounting, a housing 120 composed of a top of less width at front and terminating in an arcuate end, two side walls integral with the top, and a drive gear supporting plate adjacent to the front end of the housing and a driven gear supporting 125 plate adjacent to the rear end of the housing, the ends of both plates being attached to the side walls of the housing.

13. A brake gear mounting, comprising a 130 single piece housing consisting of a top and

two side walls, the top being apertured adjacent to the front and rear ends to provide trunnion receiving openings, a plate disposed transversely between the side walls at the front end of the housing and socketed to receive the lower trunnion of the drive gear, and a plate disposed transversely be-

tween the side walls at the rear end of the housing and apertured to receive a trunnion of the driven gear, the ends of the two plates ¹⁰ being supported on the side walls of the housing.

WILLIAM WRIGHT.
